INTEGRAL EVAPORATOR AND ACCUMULATOR AND METHOD OF OPERATING THE SAME

Arnold Dunkelman, Cincinnati, Ohio, assignor to Avco Manufacturing Corporation, Cincinnati, Ohio, a corporation of Delaware

Application March 10, 1955, Serial No. 493,414

5 Claims. (Cl. 62—126)

This invention relates to a novel evaporator particularly adapted for use in a domestic refrigerator or home freezer and to a method for operating the evaporator. The principles underlying the invention can be applied equally well, however, in commercial installations or wherever refrigerant is circulated in a closed system, such as a capillary controlled system, and vaporized in an evaporator to produce a cooling effect.

An important feature of the invention is that it provides more effectively and economically the accumulator which is conventionally used in conjunction with an evaporator. The accumulator is formed as an integral part of the refrigerant flow channel of the evaporator and, during periods of high demand, increases the heat absorbing capacity of the evaporator.

Another important feature of the invention is the novel method by which the evaporator set forth may be operated to absorb heat effectively over its entire surface area under all operating conditions with a refrigerating efficiency proportional to the demand imposed on the evaporator by ambient conditions affecting the refrigerator in which the evaporator is used.

In a conventional evaporator, formed from sheet metal stampings which are brazed together, the accumulator comprises an enlargement of a refrigerant flow pass of such size as to be able to store a sizable volume of liquid refrigerant so that variation in amount of charge can be tolerated. Although formation of such an accumulator constitutes no great problem when such a method of fabrication is employed, the accumulator does not increase the heat absorbing capacity of the evaporator significantly.

Another common fabricating method used for making evaporators involves the brazing of a sinuous length of tubing to a sheet of metal which is subsequently bent into the form of the finished evaporator. This is known as a "tube-on-sheet" type evaporator. With evaporators of this type, a spun cylindrical accumulator is normally used. The accumulator is joined to the end of the refrigerant tubing and secured in some suitable manner to the basic sheet of the evaporator to which the tube is attached. Here, the accumulator represents an additional item of cost and, again, does not improve heat absorbing capacity to any marked degree.

Recently another method of producing evaporators termed "roll bonding" has become popular. In this method, a sheet of metal, such as aluminum, is thoroughly cleaned and, using the silk screen process and a stop-weld material, the pattern of refrigerant flow channels is marked on the sheet. Thereafter another sheet of aluminum is placed against the patterned side of the first sheet, and these sheets are spot welded to hold them together. The joined sheets are then heated and passed through a rolling mill which elongates the sheets and reduces their combined thickness. Simultaneously, the sheets are homogeneously bonded over all areas not covered by the stop-weld pattern. Thereafter, a connection is made at the edge of the sheet with the convolution pattern and fluid under pressure is applied to inflate the sheets over the areas

2
covered by the stop-weld material. The sheets are placed between parallel flat platens which limit the extension of the metal in forming flow passes eventually used for conveying refrigerant. After inflation, the formed plates are bent into an evaporator.

In this type of process, which is desirable from an initial cost and simplicity standpoint, it is difficult, if not impossible, to form a large cylindrical accumulator integrally as in evaporators made from stampings. The reason is that it is not possible to stretch the metal during the inflation process to any great extent lest rupture occur. As a result, in roll bonded evaporators, the accumulator is normally formed as a relatively flat volume of quite small thickness. At intervals throughout the volume, localized areas of the opposed walls are joined for strength purposes. The resulting accumulator covers a considerable area of the finished evaporator and may create a dead spot which is objectionable under some operating conditions in failing to absorb heat. Further, because of the limitations imposed, the volume of the accumulator is quite small, which is objectionable for reasons which will appear later.

The present invention eliminates these problems and teaches an improved way to provide an accumulator in a roll bonded evaporator. Although particularly useful in this connection, it should be understood, however, that the principles involved may also be used in connection with evaporators made by other processes, as with tube-on-sheet evaporators or in evaporators formed from stampings. The principles may also be employed in connection with methods wherein sheets of metal, maintained at brazing temperatures, are pneumatically expanded between dies having the desired contour of the refrigerant flow channels.

Briefly stated, the invention comprises a particular arrangement and volume relationship of continuous refrigerant flow passages in an evaporator whereby a certain portion of the passages serve as an accumulator.

The flow passage or channel is arranged so that liquid refrigerant is conducted back and forth across the evaporator to render all portions of the adjacent surface effective in absorbing heat. The channel thereafter conveys the refrigerant gas, formed through heat absorption, back along a path lying closely adjacent to the original path. In this way, all portions of the evaporator surface are closely adjacent to the liquid refrigerant portion of the channel, which may be termed for convenience the "primary stage," as are also the portions of the return channel, termed the "secondary stage," which convey the refrigerant gas.

As will be fully described later in this specification, the secondary stage of the channel constitutes an accumulator which may be filled with liquid refrigerant to a greater or lesser extent depending upon ambient temperature conditions. To the extent that the secondary stage does carry liquid refrigerant, it aids in absorbing heat and increases the refrigerating capacity of the evaporator.

In view of the close proximity of the secondary stage to the primary stage, the gas in the secondary stage is maintained at a relatively low temperature and is relatively dense; consequently, the storage capacity of the secondary stage for liquid refrigerant is correspondingly increased.

Although the principles and structure of this invention are believed to be entirely new in the art and represent a novel advance, structures bearing *prima facie* similarity are known. For instance, reference may be made to the Levey et al. Patent 520,930 (1894) entitled "Refrigerating Machine"; also Furry et al. 2,256,021 (1941) entitled "Freezing Apparatus." These patents, however, do not relate to combined evaporators and accumulators as set forth in this application.

In view of the foregoing, it will be understood that a broad object of the invention is the provision of an improved evaporator, and more specifically an evaporator of extremely simple construction including an accumulator comprising a part of and integrally formed with the main evaporator passages.

Another object of the invention is the provision of an evaporator having a continuous flow channel, portions of which are intercalated to define a storage volume which may serve as an accumulator.

A further advantage of the invention is the provision of an evaporator which during operation has a relatively uniform surface temperature and is free from "dead areas" which do not contribute to useful refrigerating capacity.

It is also an object of the invention to provide a method of operating the novel evaporator whereby uniform absorption of heat by the entire evaporator is attained with a refrigerating efficiency proportional to the demand imposed on the evaporator.

A still further advantage of the invention is that it yields an efficient evaporator which can be very easily fabricated at low cost for use in a refrigeration system.

The novel features that I consider characteristic of my invention are set forth in the appended claims; the invention itself, however, both as to its organization and use, together with additional objects and advantages thereof, will best be understood from the following description of specific embodiments when read in conjunction with the accompanying drawings, in which:

Fig. 1 is a plan view of roll bonded sheets having a flow channel arranged according to the principles of the invention, the presence of refrigerant in the flow channel being shown diagrammatically. The figure shows the sheets as they appear in the flat prior to formation into an evaporator;

Fig. 2 is an edge view of the roll bonded sheets shown in Fig. 1;

Fig. 3 is a cross sectional view taken on plane 3—3 of Fig. 1 showing the flow channel in cross section;

Fig. 4 is a plan view of roll bonded sheets comparable to those shown in Fig. 1 but having a different pattern of flow channels illustrating a modified version of the invention;

Fig. 5 is an edge view of the structure shown in Fig. 4;

Fig. 6 is a cross sectional view of primary and secondary flow passes proportioned in accordance with another modification of the invention;

Fig. 7 is also a plan view of roll bonded sheets showing still another modification of the flow channels embodying the principles of the invention;

Fig. 8 is an edge view of the structure shown in Fig. 7;

Fig. 9 is a rear elevational view of an evaporator formed from the roll bonded sheets shown in Fig. 7, a part of the rear wall being broken away to simplify the illustration; and

Fig. 10 is a side elevational view of an evaporator formed from sheets of the type shown in Figs. 1 and 4 with the side wall partially broken away to simplify the illustration.

Before considering the functional advantages of the invention, it is well to understand the structures set forth. Directing attention first to Fig. 1, it will be noted that roll bonded sheets, generally designated 1, are formed to define a continuous refrigerant flow channel 2 extending between an inlet 3 and an outlet 4 located at one edge of the sheets. Liquid refrigerant is introduced to the inlet in any conventional manner, as by a capillary tube (not shown) and flows through the channel 2 eventually leaving by the outlet. In the course of its travel through the channel, the liquid refrigerant absorbs heat and vaporizes into a gas. Under ordinary operating conditions only refrigerant gas leaves by outlet 4.

Directing attention now to Fig. 4, it will be noted that similar roll bonded sheets are indicated at 5 and again

include a continuous channel 6 which conveys refrigerant from inlet 7 to outlet 8. The roll bonded sheets 1 and 5 of the respective Figs. 1 and 4 are arranged to be bent into an evaporator such as illustrated in Fig. 10. This type of evaporator is commonly termed a "front-to-back wrap" evaporator and in vertical section has a C formation. It is commonly positioned at the top of a refrigerator cabinet in position to receive food to be stored under low temperature conditions within volume 9. The inlet and outlet of the refrigerant flow channel are positioned at one side of the finished evaporator as illustrated by reference numeral 10 in Fig. 10.

Shown in Fig. 7 are roll bonded sheets 11 also defining a refrigerant flow channel 12 conveying refrigerant between inlet 13 and outlet 14. These sheets are designed for formation into an evaporator of the type illustrated in Fig. 9. Such evaporators are termed "side-to-side wrap" or "left-to-right wrap" evaporators since the sheets from which they are formed extend back and forth from the left to the right within the refrigerator. A rear wall 15 made of sheet metal aids in enclosing the food storage space defined by the evaporator. The inlet and outlet connections are located at the rear of the evaporator as indicated at 16.

In Figs. 1, 4, and 7, phantom lines indicate bend lines, being the points of tangency of the straight sections of the finished evaporators with the radiused corners as shown in Figs. 9 and 10.

It will be understood by those skilled in the art that evaporators of the type illustrated comprise one component of a closed refrigerant system. In the most commonly used system, a compressor is provided which compresses gaseous refrigerant and delivers it to a condenser where heat is extracted from the gas and it undergoes a change of state, returning to liquid form. The liquid refrigerant is then passed through a pressure reducing means, such as a capillary tube, from which the low pressure refrigerant liquid flows to the inlet of the evaporator. Here heat absorption causes the liquid refrigerant to return to the gaseous state. This refrigerant gas then flows through the evaporator outlet back to the compressor for a repetition of this cycle of operation. Obviously, driers and filters may be provided in the system to remove water and other impurities which would hinder its proper operation.

Returning to a consideration of Fig. 1, it will be observed that flow channel 2 extends from inlet 3 around the periphery of sheets 1, as indicated at 17. At 18 the channel departs from the periphery of the sheets and extends from right to left sinuously defining a plurality of parallel passes 19. Adjacent parallel passes are joined at opposite ends by return bends 20 and 21.

In this manner the refrigerant introduced as a liquid at 3 passes through the channel and eventually arrives at point 22. The channel from inlet 3 to point 22 is known as the "primary stage."

At 22 the refrigerant enters another series of parallel passes 23 joined at their ends by return bends 24 and 25. The last parallel pass, indicated at 26, is directly connected to outlet 4.

The portion of the channel from point 22 to outlet 4 is termed the "secondary stage" of the evaporator.

Attention may now be directed to Fig. 3 showing the cross sectional shape of the channel in the primary stage and in the secondary stage. In this figure the peripheral pass 17 is shown to the left and return bend 25 of the secondary stage is shown to the right. It will be noted that the passes have flattened top and bottom walls 27 and 28 formed by engagement of the roll bonded sheets with the platens during the inflation process, as has been described.

Attention is now specifically directed to the arrangement of parallel passes 19 and 23. It will be observed that the passes 23, which are part of the secondary stage, lie closely adjacent to and between parallel passes 19

which comprise part of the primary stage. This interspersed arrangement has been termed "intercalation."

During use, liquid refrigerant introduced at 3 passes through the primary stage where it absorbs heat and gradually vaporizes. In the course of doing so, the refrigerant flows through passes 17 and 19 and, in this way, is enabled to absorb heat from substantially the entire surface of the evaporator prior to arriving at point 22 where the mixture of liquid and gaseous refrigerant enters the secondary stage. The refrigerant then flows through the parallel passes 23 of the secondary stage where sufficient additional heat is absorbed to change the refrigerant completely into gas prior to leaving the evaporator and outlet 4. To the extent that evaporation occurs in the secondary stage, the secondary stage contributes to the refrigerating capacity of the evaporator.

The amount of liquid refrigerant present in an evaporator at any time depends upon the temperature of the air surrounding the refrigerator and the heat load on the evaporator. To illustrate, when a refrigerator is operated in a region of low temperature, the condenser readily dissipates heat which favors rapid condensation at low pressure and results in backing-up or damming-up a sizable portion of the refrigerant in liquid form in the condenser. The relatively low condenser temperature also results in a relatively low discharge pressure from the compressor and consequently in a low pressure differential across the capillary tube which conveys liquid refrigerant to the evaporator. Under such conditions, only a portion of the total refrigerant charge is present in the evaporator as liquid. At such time, the secondary stage of the evaporator runs substantially dry, i. e., is filled with refrigerant gas rather than liquid. It will be appreciated that little or no accumulator capacity is necessary under such conditions.

The need for an accumulator will be understood from a review of conditions prevailing when the refrigerator operates in a region of high ambient temperature. The higher condenser temperatures then prevailing result in higher condenser pressure and less damming of liquid refrigerant in the condenser. As a result, an increased pressure differential exists across the capillary tube supplying the evaporator, and an increased portion of the liquid refrigerant is present in the evaporator. Under such operating conditions, an accumulator is necessary to accommodate the increased amount of liquid and, in the present invention, the passes of the secondary stage are partially or totally filled with liquid refrigerant to the extent required. The secondary stage then functions much as the primary stage and contributes to the refrigerating capacity of the evaporator. The importance of this feature will be appreciated when it is recognized that evaporator capacity increases with ambient temperature and compensates for the correspondingly greater heat leak into the refrigerator then prevailing.

From an ideal design standpoint, the primary stage should be made just large enough to have sufficient heat absorbing capacity for the needs of the refrigerator when operating at the lowest ambient temperature to be encountered. Since the increase in the amount of liquid refrigerant present in the evaporator is related to ambient temperature rise, it will be appreciated that the extremes of ambient temperature conditions between which satisfactory operation is possible is a function of the accumulator capacity. The extremes for which domestic refrigerators are normally designed are 50-110° F. For this reason, it is desirable to provide large accumulator capacity, which may be effectively accomplished by the present invention.

The accumulator also compensates for variations in the amount of refrigerant with which the system is initially charged. A large accumulator simplifies charging by providing increased charge tolerance.

Returning to a consideration of Fig. 1, it will be noted that the primary and secondary stages, being intercalated,

leave no areas of the evaporator which might operate at an elevated temperature. Instead, low temperatures generally prevail through the evaporator and, in fact, the primary stage tends to lower the temperature of the secondary stage and the gas therein, thereby increasing its liquid storage capacity.

As suggested earlier in the specification, dead areas of relatively high temperature are very objectionable in an evaporator since the frost, which normally accumulates on an evaporator, may tend to melt in the dead areas.

The flow channel of Fig. 1 has been cross hatched to indicate the disposition of refrigerant under typical operating conditions between the extreme ambient temperatures for which the refrigerator is designed. It will be understood that the refrigerant, which enters as a liquid at 3, gradually vaporizes as it absorbs heat in the primary stage. The gas and liquid mixture has been indicated by double cross hatch lines.

Since a portion of the secondary stage must function as an accumulator at any ambient temperature above the minimum design temperature, the liquid and gas mixture has been shown filling the secondary stage to point A. The remainder of the secondary stage is filled with refrigerant gas maintained at low temperature by the adjacent primary stage, as has been explained.

The function of the primary and secondary stages is the same regardless of the disposition of the sheets, either as shown in Fig. 1 or as in Fig. 10.

The refrigerant and integral evaporator and accumulator constitute a novel combination embodying the principles of the invention. The disposition of the refrigerant at ambient temperatures above the minimum is substantially the same in the structures shown in Figs. 4 and 7 as indicated in Fig. 1, i. e., a portion of the mixture of refrigerant gas and liquid will be present in the secondary stage, and the primary stage will be full as indicated.

The configuration of the flow channel shown in Fig. 4 embodies somewhat the same principles as in Fig. 1.

It will be noted, however, that the primary stage extends from inlet 7 to point 29 where the refrigerant gas and liquid enters the secondary stage. The secondary stage extends from point 29 to outlet 8.

The parallel passes 36 and 31 of the primary and secondary stages, respectively, are again intercalated as has been described in connection with Fig. 1. It should be observed, however, that additional passes 32, 33, and 34 have been provided conveying the refrigerant from the parallel passes to the outlet 8. These additional passes again are located quite close to portions of the primary stage to assure temperature uniformity and maximum effectiveness of the secondary stage in acting as an accumulator.

To increase the refrigerating capacity of the primary stage, parallel flow passes may be provided as at 35 and 36. The primary stage may reverse in direction, as at 37, to avoid mechanical fasteners which extend through holes 38 in connection with the attachment of defroster-heaters and controls.

A plurality of holes 39 may be formed adjacent each side edge of the sheet to accommodate rivets used for securing end panels to the evaporator after it is formed to the shape shown in Fig. 10.

In Fig. 7, the primary stage extends from inlet 13 to point 40. The secondary stage extends from point 40 to outlet 14.

It will be noted that branched passes 41-45 have been provided in the primary stage to increase the refrigerating capacity of the structure, particularly near the edges where heat transfer is greatest. The primary stage also includes a plurality of parallel passes 47 which are intercalated with parallel passes 48 of the secondary stage.

It will be noted that the inlet 13 and outlet 14 of the structure shown in Fig. 7 are relatively remote when the

sheet 11 is in the flat. When the sheet is formed into the configuration shown in Fig. 9, the inlet and outlet are brought close together to facilitate connection in the closed refrigerant system which has been described.

A series of holes 49 may be provided along one edge to facilitate attachment of the rear wall. The left and right ends of the sheet are also provided with holes 50 to permit riveting, as illustrated at 51 in Fig. 9.

From what has been said, it will be understood that it is desirable to provide as large an accumulator, and hence a secondary stage, as possible. Although for many applications it is desirable to make the secondary stage larger than the primary stage, it is recognized that for some usage the secondary stage may actually be smaller. To illustrate, in Fig. 1 the ratio by volume of the primary to the secondary stage is in the order of 60:40.

In the structure shown in Fig. 4, the primary and secondary stages have equal length and the passes have cross sections of equal area. As a result, the primary and secondary stages have substantially identical internal volumes.

In the structure shown in Fig. 7, the volume ratio of the primary stage to the secondary stage is in the order of 55:45.

The cross sectional width of the flow channel that may be used in a roll bonded evaporator is a function of operating pressure, as well as thickness of the sheets which are bonded together. In evaporators of the type illustrated made from 250 aluminum, the wall thickness of the passes as finally formed is approximately .030 inch and the evaporator must withstand test pressures of 350 p. s. i. g. For these parameters, maximum cross sectional width of the flow channel is approximately $1\frac{1}{32}$ of an inch. As a practical matter, it is desirable to provide flow paths of this maximum width in both the primary and secondary stages. For this reason, increased capacity of the secondary stage is usually accomplished by providing increased length of flow channel in the secondary stage.

In other processes, however, where no dimensional limitation is imposed, it is desirable to make the cross sectional area of the passes in the secondary stage larger than in the primary stage. This is illustrated in Fig. 6 which indicates a pass 52 of a primary stage immediately adjacent a pass 53 of a secondary stage. It will be noted that the secondary stage has a considerably larger flow area than the primary. Increased passage height, as well as width, may be employed to increase cross sectional area.

A similar relationship of flow areas may be utilized in roll bonded evaporators if the thickness of the sheets are appropriately increased. Although this is possible, it is frequently not desirable because of the increased cost resulting from use of thicker material and different alloys.

Thus, control of accumulator volume in the secondary stage is a function of channel length as well as channel cross section. Either length of cross sectional area or both may be varied as desired to provide a large secondary stage with ample accumulator capacity to meet the requirements of the refrigerator.

The left-to-right type evaporator lends itself particularly well to application of this invention. This style of evaporator has more surface area, and hence can accommodate a longer refrigerant channel, than a front-to-back evaporator. Since only a certain size primary stage is required for given refrigeration requirements, the additional refrigerant channel may be devoted to accumulator volume.

Recently there has been made available to the industry a process for roll bonding several layers of sheets together simultaneously. In this way, for example, three sheets of material may be joined simultaneously to provide two series of flow channels which, although they

may be overlapped, are none the less separated by an intermediate sheet of material. This type of structure also lends itself well to the application of this invention since one flow channel may be devoted to the primary stage and the other flow channel, on the other side of the intermediate sheet, may be devoted to the secondary stage. The resulting operation will be essentially the same since the principles of uniform temperature distribution and low secondary stage temperatures may be attained, and a large accumulator volume may be provided in the secondary stage without the use of a separate accumulator.

In view of the foregoing, it will be appreciated by those skilled in the art that through this invention an evaporator of improved efficiency and refrigerating capacity has been provided. The need for a separate accumulator is eliminated and the refrigerant flow channel itself is used for this purpose. The refrigerant liquid that may be present in the accumulator aids in absorbing heat in a manner far more efficient than possible with conventional accumulators.

The various features and advantages of the design and construction disclosed are thought to be clear from the foregoing description. Various other features and advantages not specifically enumerated will undoubtedly occur to those versed in the art, as likewise will many variations and modifications of the preferred embodiments of the invention illustrated, all of which may be achieved without departing from the spirit and scope of the invention.

Having described a preferred embodiment of my invention, I claim:

1. The method of operating a refrigerator evaporator formed from a rigid metallic sheet and a continuous flow channel for conveying liquid and gaseous refrigerant, the first portion of which channel is positioned to absorb heat from the entire area of the sheet and the second portion of which is disposed in heat transfer relationship with the first portion comprising maintaining the first portion of the channel full of liquid and gaseous refrigerant mixture at all times, filling the second portion of the channel with such mixture only to an extent proportional to the rate of heat absorption required of the evaporator, and filling the remainder of the second portion with refrigerant gas, whereby the entire area of the evaporator is effective in absorbing heat at all times and the refrigerating capacity of the evaporator is adjusted as required to meet prevailing demands for refrigerating capacity.

2. The method of continuously operating a refrigerator evaporator having a metallic sheet with which a refrigerant channel is associated in heat transfer relationship, the channel including a first portion for absorbing heat from substantially the entire area of the sheet and a second portion in heat transfer relationship with the first portion comprising maintaining liquid refrigerant in the first portion at all times and maintaining liquid refrigerant in the second portion only to an extent commensurate with prevailing requirements for refrigerating capacity.

3. The method of continuously operating a refrigerator evaporator having a sheet with which a refrigerant channel is associated in heat transfer relationship, the channel including a first portion for absorbing heat from substantially the entire area of the sheet and a second portion in heat transfer relationship with the first portion comprising maintaining liquid refrigerant in the first portion at all times and maintaining liquid refrigerant in the second portion to an extent proportional to ambient temperature conditions affecting the refrigerator in which the evaporator is located.

4. The method of producing refrigeration by use of an evaporator including a conduit for conveying refrigerant in liquid and gaseous form comprising passing liquid refrigerant through a first portion of the conduit in heat exchange relationship with substantially the entire area of

said evaporator, and then passing liquid refrigerant and gaseous refrigerant formed during said first step through a second portion of the conduit in heat exchange relationship with the first portion.

5. The method of producing refrigeration comprising conveying liquid refrigerant into heat absorbing relationship with a surface to be refrigerated and then conveying refrigerant gas resulting from absorption of heat from the surface and any remaining refrigerant liquid into intimate heat transfer relationship with portions of the refrigerated surface. 10
